WEFT STOP MOTION FOR NARROW
FABRIC LOOMS

Melvin Siegel, East Paterson, N. J.

Application December 3, 1952, Serial No. 323,859

2 Claims. (Cl. 139—371)

1

This invention relates to a means upon a loom for automatically stopping same when the weft yarn supply upon a bobbin or quill in a shuttle becomes exhausted and bares the quill. The invention has particular reference to looms which weave ribbons, tapes, labels, elastics, or other narrow fabrics having a plurality of bobbin carrying shuttles all operating at the same time.

When a quill carrying a weft yarn becomes empty and the loom continues running, imperfect fabric results. The loom must be constantly watched for empty weft quills.

The object of this invention, is therefore, to provide a means for stopping the loom or indicating when the weft yarn supply is exhausted. An electrical circuit with the quill of an exhausted weft yarn to actuate a switch in the power line, is employed.

A master shuttle is provided upon which there is mounted a quill having a weft yarn several yards shorter than all other weft yarns upon all other quills operating upon the loom, and providing the said master shuttle with electrical terminals which, when the weft yarn is exhausted, permit a finger or trigger, normally engaging the weft yarn which provides tension, to contact a metal core upon the quill, thus completing an electrical circuit through the bow or bridge wires on the shuttle and contact finger on the block. This closed low voltage electric circuit operates a relay or solenoid switch and opens a power circuit to stop the motor which drives the loom. This electrical circuit may also stop the loom through a mechanical linkage actuated by a solenoid, but not shown.

A further object resides in the provision of a signal or alarm means to indicate the stoppage of the loom.

A still further object of this invention is the provision of an assembly in which the constituent elements are so arranged structurally and functionally as to assure improved results with materials and members which may be manufactured at reasonable cost, may be easily assembled and which will be efficient in operation with minimum wear to the parts.

The best embodiment of the invention has been chosen for illustrative purposes, but this embodiment should be viewed as being illustrative only and not as limiting because obviously the invention is capable of other embodiments having revised details of construction, so long as they fall within the ambit of the appended claims.

The invention itself, however, both as to its organization and its method of operation, will

2

best be understood from the following description of a specific embodiment when read in connection with the accompanying drawings, in which:

Fig. 1 is a top or plan view showing a shuttle partly broken away, and showing a portion of the batten upon a loom.

Fig. 2 is a front view, partly in section, the sectional portion being taken along a plane indicated by the line 2—2 of Fig. 1.

Fig. 3 is a side elevational view looking in the direction indicated by the arrow X in Fig. 1 showing portions of the batten of a loom, in section, and diagrammatically shows the electrical circuit employed.

Fig. 4 is a fragmentary detail of a part of the shuttle and is taken in a plane approximately along line 4—4 of Figs. 1 and 2.

Fig. 5 is a fragmentary detail of a part of the shuttle taken along line 5—5 of Figs. 1 and 2, and

Fig. 6 is a fragmentary detail similar to Fig. 4, but shows a modified form.

Referring to the parts in detail wherein similar reference numerals represent similar parts throughout, 10 and 12 represent parts of supporting metal cross bars of the batten on a loom; 14 is a rack having reciprocal movements within the grooved beam 16. Wooden shuttle blocks 20, having arcuate or straight grooves 22, are secured upon the cross bars 10 and 12 by means of screws 24 and 26 respectively. Wooden shuttles 28, having grooved inner bases conforming to the arcuate grooves 22 upon the shuttle blocks 20, are reciprocally movable upon the said shuttle blocks and are formed with recessed rack 30 (Fig. 3) which are engageable with pinion gears 32 mounted upon the shuttle blocks 20. The said pinion gears 32, by their engagement with the reciprocating rack 14, impart reciprocal movement to the said shuttles. When the rack moves in the direction indicated by the arrow A the shuttles will move in the direction indicated by the arrow A'. When the rack 14 moves in an opposite direction or as indicated by the arrow B the shuttles will move in the direction indicated by the arrow B' (Fig. 2). Reciprocal movement is imparted to the rack by straps, pulleys and levers or by any conventional means (not shown).

A metal quill 34, around which the weft yarn (not shown) is wound is carried upon a metal shaft 36 which is held at one end in a metal bushing 38 which is formed with an outwardly extending portion 40 and at its other or opposite end is held in a groove 42. The portion 40 has a bore to receive one end of a bow wire 44 while its opposite end engages in a bore in the shuttle 28, as

at 46. Thus the said bow wire 44 may have electrical contact with the quill 34 and shaft 36.

A second bow wire 48 is mounted at one end 50, in a metallic block 52 on said shuttle 28 and while its opposite end is secured in a bore 54 upon the said shuttle. The metallic block 52 will establish an electrical connection with the said bow wire 48. A trigger 56 is pivotally mounted in the said metallic block 52 and has a free end 58 which is adapted to engage against the outer layer of weft yarn (not shown) upon the quill and with the quill 34 when the weft yarn upon the quill is exhausted thus making a circuit connecting bridge between the two said bow wires 44 and 48. A flat trigger spring 60 is securely fastened at one end 62 to the shuttle while its free end 64 has sliding engagement with the said trigger 56 and acts to urge the said trigger against the weft yarn upon the quill and against the quill 34 when the weft yarn is exhausted. This contact will complete a bridge which will act as a circuit closing element when the shuttle 28 has reciprocal movement in the grooves 22. Upper terminal spring contact fingers 64' extend outwardly from plates 66 secured to and held upon adjacent shuttle blocks 20, by means of aforesaid screws 24 and are grounded to the frame of the loom by said screws 24. Lower terminal contact springs 68 extend outwardly from plates 70 secured to and held upon adjacent shuttle blocks by means of screws 72. The said plates 70 are formed with orifices 74 larger than the screw head and prevent any contact with the screws 26 thus insulating said plates and their attached springs 68 from the loom frame and ground.

When the shuttle 28 reciprocates in its arcuate groove 22, the bow wires 48 and 44 upon the said shuttle will, in its movement, contact the extending spring fingers 64' and 68, respectively and when the weft yarn upon the quill is exhausted these contacts, coacting with the said bow wires 44 and 48, will close a low voltage circuit through a line 76, to a transformer 78 and a relay unit thereby actuating a solenoid 80 to open a power circuit switch 82 to a motor 24 and stop a loom.

The shuttles as shown, are adapted to reciprocate upon shuttle blocks in an arcuate line. Shuttles or shuttle blocks however, may be designed for a straight horizontal movement of the shuttles and may also be arranged in two or more tiers or decks instead of one as shown.

In operation, fully threaded weft bobbins may be placed within the shuttles. The trigger 56 will ride against the outer layer of the wound thread and as the weft thread is used and unwound, the trigger end 58 which contacts the thread, will follow toward the central metal core 34 and when the said core is bare and the bow wires 44 and 48 contact the fingers 64' and 68, an electrical current will be established to the relay.

When a loom is loaded with bobbins, all the bobbins but one are wound with the same length of weft thread. The one exception will be several yards shorter and goes into a master shuttle. When this bobbin is unwound the motor circuit will be broken and so stop the loom, or the alarm will sound or the signal light become illuminated. All of the bobbins, throughout the tier or tiers, are changed or the shuttles recharged.

In Fig. 6 there is shown a modified form for

establishing electrical contact between the core 36 and bow wire 44 which consists of a short wire or flat metal strip 90 soldered at both ends to a bushing 92 and directly to the bow wire 44. The bow wire 48 is connected to the flat trigger spring 60—62 by means of a wire or flat metal strip 94 which is soldered at one end to the bow wire and at the other end to the flat spring.

The drawings show a single shuttle and a pair of adjacent shuttle blocks arranged to stop the loom. Every shuttle in the loom, however, may be arranged mechanically as indicated in the drawings, so that if the filling is exhausted in any one, the loom will stop. Also, as shown with two adjacent blocks, the circuit will be completed; when the filling supply is exhausted, on every pick or beat-up of the loom. By only having one block so equipped, it will indicate on every other pick when the filling supply is exhausted.

I claim:

1. A stop mechanism for looms comprising in combination with a shuttle reciprocally movable upon a loom, said mechanism having a metal quill having a weft yarn thereon, a metallic shaft upon the shuttle to carry the quill, a metallic trigger finger pivotally secured at one end to the shuttle and having its free end engageable against the weft yarn upon the quill and adapted to move inwardly against the outer surface of the weft yarn and make contact with the metallic quill when the weft yarn is completely unwound, a spring member secured at one end to the shuttle and having its free end in slidably engagement with the metallic trigger to urge same inwardly, a metallic bushing to receive the pivotal end of the metallic trigger and having electrical connection therewith, and a second metallic bushing adapted to receive one end of the quill holding metallic shaft and having electrical connection therewith; a bow wire contact member extending from the said shuttle and having electrical contact with the quill shaft bushing and quill shaft, a second bow wire contact member extending from the said shuttle and having electrical contact with the metallic trigger bushing and trigger, a pair of resilient spring members secured to and grounded to the loom frame, a second pair of resilient spring members secured to the loom frame and insulated therefrom, adapted to contact the said bow wires on the shuttle as said shuttle reciprocates upon the shuttle block and close an electrical circuit when the weft thread upon the quill is completely unwound to allow the metallic trigger to contact the quill and the quill shaft and direct an electrical current through lines to a solenoid to open a switch in a power line to a motor drive and stop the loom.

2. A stop mechanism as set forth in claim 1 wherein the said bow-wires are electrically connected to the quill and shaft and said spring member and trigger by means of a soldered joining wire or metal strip.

MELVIN SIEGEL.
